UNITED STATES PATENT OFFICE.

GEORGE A. JOHNSON, OF CHICAGO, ILLINOIS, ASSIGNOR TO WILLIAM H. MINER, OF CHAZY, NEW YORK.

SIDE BEARING FOR CARS.

1,273,866.

Specification of Letters Patent. Patented July 30, 1918.

Application filed November 20, 1916. Serial No. 132,312.

To all whom it may concern:

Be it known that I, GEORGE A. JOHNSON, a citizen of the United States, residing at Chicago, in the county of Cook and State of Illinois, have invented a certain new and useful Improvement in Side Bearings for Cars, of which the following is a full, clear, concise and exact description, reference being had to the accompanying drawings, 5 forming a part of this specification.

This invention relates to improvements in side bearings for cars.

The object of the invention is to provide an anti-friction side bearing for railway cars 15 so arranged that a uniform distance will always be maintained between the bolsters during the relative rotating movements and having the anti-friction roller adapted to return to normal position under the influence 20 of gravity.

In the drawing forming a part of this specification, Figure 1 is an end elevation of portions of a body and truck bolster of a car showing my improvements in connection 25 therewith. Fig. 2 is an enlarged vertical sectional view taken substantially on the line 2—2 of Fig. 1 and showing the parts in normal position. Fig. 3 is a view similar to Fig. 2, but illustrating the position of the 30 parts at the end of a movement. And Fig. 4 is a sectional view taken substantially on the line 4—4 of Fig. 2. In said drawing, 10 denotes a body bolster of a car and 11 a truck bolster pivotally connected thereto. 35 The body bolster is shown as provided with an integral bearing surface 12 with depending flanges 13—13 at the sides thereof. Secured to the upper face of the truck bolster is a base casting 14 of box-like form and 40 having a concave upper bearing surface 15. The casting 14 is provided with side flanges 16—16 by which the anti-friction roller 17 is prevented from accidental displacement. It 45 will be noted that the ends of the casting 14 are provided with curved shoulders 18—18 to limit the movement of the roller.

Carried by the body bolster 10 between the flanges 13 is a rocker 19 having a normally horizontal bearing surface 20 and a 50 convex upper bearing surface 21 adapted to engage said surface 12. The rocker 19 is supported by means of a pin 22 which extends transversely through the rocker and through enlarged openings 23 in the side flanges 13. The pin 22 is prevented from

displacement and also held in its uppermost position by means of springs 24—24 attached thereto and also to suitable eyes 25 on the under surface of the body bolsters.

The side flanges 16 of the base casting are 60 recessed as indicated at 26 in order to permit dirt or other foreign matter to pass out and prevent clogging of the roller.

The curvature of the surface 21 is so designed with respect to the curvature of the 65 surface 15 that, as the roller travels to either side of normal position during operation of the side bearing, the vertical distance between the line of contact of the roller 17 with the surface 15 and the line of contact of the surface 21 with the surface 12 will always remain the same. By this means, the spacing between the two bolsters is maintained uniform during the relatively rotating movements. Normally, the rocker 19 is 70 slightly spaced from the roller 17, but when the weight is transferred to the bolster 10 so as to bring the rocker 19 into engagement with the roller, the roller will be revolved and move to either side of its normal position as the body bolster and truck bolster 75 turn relatively to each other. Due to the rocking movement of the member 19, it is apparent that the pin 22 will be forced downwardly within the enlarged openings 80 23 and against the action of the springs 24. Upon release of the pressure on the side bearing, the pin 22 together with the rocker 19 will be lifted and the rocker centered as 85 shown in Fig. 2. This will eliminate the contact between the roller and the rocker thereby permitting the latter to return to central or normal position under the influence of gravity down the curved surface 90 15.

I claim:

1. In a side bearing, the combination with members having upper and lower bearing surfaces, of a roller mounted on the lower bearing surface and adapted to be returned to normal position by gravity, and a rocker in engagement with said upper bearing surface and against which the roller bears during operation.

2. In a roller side bearing, the combination with a lower member having a concave upper bearing surface, of a roller mounted thereon, a second member having a plane bearing surface, a rocker having an upper convex surface engaging said 105 110

horizontal surface, the rocker having a lower horizontal surface disposed above the roller and with which the latter is adapted to engage.

3. In a side bearing, the combination with two opposed members, one having a concave surface and the other a flat surface, and a rocker and a roller interposed between said surfaces, the roller engaging said concave surface and the rocker said plane surface.

4. In a side bearing for cars, the combination with a base casting adapted to be secured to a truck bolster, said base casting having a concave bearing surface in its upper face, of a roller mounted on said surface and adapted to be returned thereby to

normal position under the influence of gravity, a rocker disposed above said roller, said rocker having a lower horizontal surface 20 over the roller and a convex upper surface, and spring controlled means for supporting said rocker from a truck bolster, the curvature of said concave and convex surfaces being such that the distance between the line 25 of contact of the roller with the concave surface and the convex surface of the rocker with the body bolster remains uniform during the actuation of the side bearing.

In witness that I claim the foregoing I 30 have hereunto subscribed my name this 16th day of Nov. 1916.

GEORGE A. JOHNSON.
